SOLE-FITTING MACHINE

Arthur Alan Rivington, Leicester, England, assignor to United Shoe Machinery Corporation, Paterson, N. J., a corporation of New Jersey

Application November 15, 1937, Serial No. 174,578
In Great Britain November 26, 1936

8 Claims. (Cl. 12—27)

This invention relates to sole-fitting machines and is herein illustrated as embodied in a machine adapted to cut a channel and also a stitch-receiving groove in an outsole. A type of machine commonly used for performing these operations is provided with a sole support in the form of a driven toothed feed wheel and an edge gage in the form of a driven roll, both mounted in a stationary frame for movement transversely 5 of the direction of feed to vary the distance of the channel from the edge of the sole. Machines of this type are further provided with a head mounted on the stationary frame for heightwise movement in accordance with variations in the 10 thickness of the soles being operated upon. This head carries the channeling and grooving instrumentalities as well as a driven roll engaging the upper surface of the work, and a presser foot for gaging the heightwise position of the head in accordance with the thickness of the sole.

It is an object of the present invention to provide an improved machine of the type above referred to. In accordance with the invention, the machine illustrated herein is provided with an improved arrangement for carrying the channeling and grooving knives, an improved mechanism for raising the grooving knife out of operative position, an improved arrangement of the feed wheel and edge gage roll which facilitates lateral movement of those members, and with other improvements which will appear in the detailed description which is to follow.

The various details of construction and combinations of parts of the improved machine will now be described in connection with an illustrative machine and pointed out in the appended claims.

Referring now to the accompanying drawings, Fig. 1 is a view in front elevation of an illustrative machine showing the margin of the shoe sole in position to be operated upon;

Fig. 2 is a rear view of the upper part of the machine;

Fig. 3 is a sectional view showing the arrangement of an edge gage of the machine;

Fig. 4 is a diagram showing the relative positions of certain of the work-engaging parts of the machine;

Fig. 5 is a view showing the arrangement of one of the treadles of the machine; and

Fig. 6 is a sectional view showing details of certain parts of the machine.

In the illustrated machine the work, for example a sole S, as shown in Fig. 1, is engaged marginally on its under side by the periphery of

a driven toothed feed wheel 20 and is pressed against the feed wheel partly by the periphery of a smooth driven upper presser wheel 22 which engages the upper side of the work and partly by a presser foot 24 mounted adjacent to the presser wheel 22. The margin of the work is fed between the wheels 20, 22 past a stationary channeling knife 26, the feed wheel 20 rotating anti-clockwise, viewing the wheels from the left as in Fig. 4, and the presser wheel 22 rotating clockwise. The 10 channeling knife 26 engages the work to cut a marginal channel therein; the knife 26, the presser wheel 22 and the presser foot 24 being mounted in a head 28 which is yieldingly urged 15 downwardly towards the feed wheel 20. The 20 heightwise position of the head 28 is gaged from the upper surface of the work piece by the presser foot 24, and the channel cut by the knife 26 therefore remains at the same depth below the upper surface of the work regardless of the thickness of the work. A grooving knife 30, mounted 25 for operation on the work after the channeling knife 26, is provided for cutting a stitch-receiving groove in the base of the channel. There is provided also a driven rotary edge gage 76 the position of which with regard to the knife 26 determines the distance of the channel from the edge of the work.

The supporting structure of the illustrated machine comprises a stationary main frame 32 having a depending portion (not shown) whereby it is mounted for heightwise adjustment upon a suitable base which in turn may be secured upon a work bench. Integral with the frame 32 and extending upwardly from the right and left hand ends thereof, respectively, as viewed in Fig. 1, are two lugs 34 and 36. In the following description the relation of the various parts of the machine to each other will be described as seen in Fig. 1 unless otherwise mentioned.

Mounted in bearings at the bottom of the two lugs 34 and 36 is a driving shaft 38. The driving arrangements for the shaft 38, which are not shown herein, are of a well-known type disclosed in United States Letters Patent No. 1,004,614, granted October 3, 1911, upon the application of Henry W. Winter, and comprise a crank handle at the right-hand end of the shaft assisted by a power-driven pulley which is loosely mounted on the shaft and which may be coupled thereto through a clutch mechanism controlled by the crank handle. The shaft 38 through a pinion 39 drives an intermediate pinion 40 mounted on a shaft 41 journaled in the lugs 34 and 36. The pinion 40 drives a gear 48 secured upon a shaft 42 50 55

which carries the feed wheel 20 and which is journaled in suitable bearings formed in the lugs 34 and 36. The shaft 42 is constrained against axial movement to the left by a washer 44 secured upon its right-hand end and bearing against the right-hand side of the lug 34. A collar 46 integral with the shaft 42 holds the latter against endwise movement to the right by engagement with the left-hand side of the lug 36.

10 Mounted upon an extension 61 of the shaft 42 is the feed wheel 20. The feed wheel comprises four work-engaging annular toothed sections 50 coaxial with the shaft 42, each of which is capable of movement in an anti-clockwise direction, as seen from the left-hand end of the machine, independently of the shaft 42, but is prevented from moving clockwise, except with the shaft, by a Horton clutch device similar to that disclosed in the above-mentioned patent to Winter No. 1,004,614.

15 This clutch device comprises a flat annular disk 45 having three circumferentially tapering recesses cut therein in each of which is accommodated a disk roll 49. Each roll 49 is urged in a clockwise direction with reference to the disk 45 by a spring, the arrangement being such that when the annulus 50 tends to move clockwise (with respect to an observer positioned to the left of the machine as seen in Fig. 1) with regard to the disk 45, the roll 49 is urged by the spring into a part of the recess 47 which is of relatively small radial depth; the action of the relative movement between the disk 45 and section 50 then causes the roll 49 to wedge the disk 45 and section 50 together to prevent clockwise movement of the annulus 50 relatively to the disk 45.

20 When the section 50 is moved anti-clockwise with reference to the disk 45 the roll 49 remains in a part of the recess 47 which is of such a radial depth that no wedging action can occur, being held against the action of the spring 51 by the relative movement of the section 50 and disk 45. Such freedom of the sections 50 to turn independently of each other in the direction of feed facilitates operation upon work pieces having sharply curved portions.

25 The four disks 45 and the four sections 50 are held in assembled relation by screws 55 passing through holes 53 in the disks 45. Four of the sections 50 are shown in the feed wheel 20, such a number being convenient to use for men's heavy footwear, but the number of sections may be varied as required.

30 The sections 50 are held together between two disks 52 and 54 having smooth peripheries, the radius of these disks being slightly less than that of the sections 50 so that the teeth of the sections 50 can engage the work. The heads of the screws 55 abut the left-hand side of the left-hand disk 52 and the screws 55 then pass through holes in the disk 54 and are threaded into a bevel gear 56, the arrangement being such that the screws 55 serve to hold the disks 45, 52, 54 and bevel gear 56 together as a unit. A boss 257 extends to the left from the disk 54 and is mounted on the extension 261. From the center of the bevel gear a boss 58 extends to the right which carries a circumferential groove 60. The bosses 257 and 58 have keyways therein which engage keys 259 on the extension 261, whereby it is ensured that the feed wheel assembly comprising the disks 52, 54, the sections 50 and their internal clutch devices, the bevel gear 56 and the bosses 257, 58 shall rotate anti-clockwise when turned by the shaft 42, while the assembly is capable of a small axial sliding movement upon the extension 261. A washer 263

upon the end of the shaft 42 retains the feed wheel assembly upon the shaft while the machine is being assembled.

The feed wheel assembly is urged to the left as a unit by the action of a heavy spring 62 (Fig. 3). The spring 62 is accommodated in a box 64 secured to the lug 36. At its right-hand end the spring 62 engages one end of a screw 66 threaded into the right-hand wall of the box 64, while at its left-hand end the spring presses against a member 68 arranged to slide from right to left in the box 64 and carrying two depending arms, one of which is indicated by the reference numeral 70 in Fig. 1, which constitute a yoke. This yoke straddles the boss 58 and the arms thereof extend into the groove 60. In this way the spring 62 operates to urge the feed wheel assembly to the left; the end of the screw 66 extends through the right-hand wall of the box 64 and may be turned to adjust the pressure exerted by the spring 62.

The slide 68 carries a stud 72 on which is mounted a knurled wheel 76. Secured beneath the knurled wheel is a small bevel gear 74 arranged to mesh with and be driven by the bevel gear 56. The knurled wheel 76 constitutes the driven rotary edge gage of the machine and its left-hand edge is arranged to be approximately in the same vertical plane as the right-hand face of the disk 54. The member 68 and the feed wheel assembly move as a unit as a result of the connection between them effected by the aforesaid yoke and the groove 60 and consequently movement of the edge gage 76 and the feed wheel assembly axially of the shaft 42 does not interfere with the proper meshing of the two bevel gears 56 and 74 through which the edge gage 76 is driven from the shaft 42. An advantage of this arrangement is that when the edge gage 76 is moved to the right no gap is opened up immediately beneath the operative parts of the machine into which scraps of the work piece can fall to hinder the return movement of the gage 76 under the action of the spring 62. The member 68 carries sheet metal guards, one of which is indicated by the reference numeral 78, the front and rear portions of which are shaped to extend into the angle between the edge gage 76 and the disk 54. The rear guard carries clearers in the form of pointed fingers (not shown) which extend into the axial gaps between the sections 50 and serve to clear out waste material which tends to accumulate in these gaps and cause clogging of the teeth of the feed wheel 20. The two guards are readily detachable from the member 68 to provide access to the bevel gears 56 and 74 and other parts concealed beneath them. In adapting the machine to operations which do not require the edge gage 76 to be driven the bevel gear 74 may be omitted.

The feed wheel assembly is retracted against the action of the spring 62 by means of a treadle 51, Fig. 5. Due to the heavy character of the spring 62 the treadle mechanism is preferably of a compound nature to provide adequate leverage in small compass and comprises a treadle lever 53 fulcrumed at its rear end upon a pin supported by a floor plate 55 and coupled to an upwardly extending treadle rod 78 at its forward end. The treadle 51 is fulcrumed upon a pin 57 supported by the floor plate 55 at a point above the lever 53 about two-thirds of the way along the lever 53 from its rear end and comprises a tread plate 59 extending forwardly and an intermediate flat part having a lug 61 adapted to engage the upper surface of a cam piece 63 integral with the lever 53 about five-sixths of the

way along the lever 53 from its rear end. This arrangement provides a convenient method of obtaining a leverage of considerable magnitude. The treadle rod 78 extends upwardly, passing through a hole in the end of a long arm 80 of a double lever 80, 82 (see Figs. 1 and 3) and has adjusting nuts threaded on its end. The double lever 80, 82 is fulcrumed about a pin 84 secured in the lug 36 and a small arm 82 of the double lever 80, 82 extends upwardly behind the box 64. The end of the small arm 82 has a recess which accommodates a square block 86 for sliding movement vertically therein. The block 86 is pivoted on a pin 88 integral with the member 68 and extending through a slot in the back of the box 64. Depression of the treadle 51 moves the slide 68 to the right and consequently also the feed wheel assembly and the edge gage 76. A screw 90 threaded into the lug 36 and engaging the underside of the arm 80 limits movement of the slide 38 to the right when the treadle is depressed, while movement of the slide 68 to the left under the action of the spring 62 is limited by a similar screw 92 which engages the upper side of the arm 80.

The head 28 of the machine is mounted upon the lugs 34 and 36 of the main frame 32. To provide for such mounting each of the lugs 34 and 36 has its upper portion in the form of a pair of spaced parallel ears, and the head 28 has a pair of depending lugs 94 and 96 which are received between the respective pairs of ears. The lug 96 has a pair of finished surfaces 97 (Fig. 1) and 99 (Fig. 2) which enable it to slide transversely between the ears which constitute the upper part of the lug 36.

The lower part of the lug 94 is similarly provided with finished surfaces so that it may slide between ears upon the lug 34. This arrangement allows adjustment of the head transversely, i. e. from left to right or vice versa, the adjustment being controlled by a screw 98 threaded transversely in the lug 96 and having a circumferential groove 100 into which are accommodated projections, one of which is indicated by the numeral 102, forming part of the lug 36 of the frame 32; the screw 98 is provided with a capstan head 104 by which the adjustment is facilitated. The ears forming part of the lug 34 provide bearings for a pin 106 which passes through an open-ended transverse slot 108 in the lug 94 of the head 28. The pin 106 provides a pivot about which the head 28 may swing, while the slot 108 accommodates the transverse adjustment aforesaid. A small amount of swinging may take place without prejudice to the meshing of the gear 48 with a gear 110 mentioned hereinafter, due to the nature of the teeth of these gears. It will be observed that the head 28 may readily be detached from the frame 32. The above-described arrangement for mounting the head 28 on the frame 32 is similar to that disclosed in British Letters Patent No. 315,812, dated January 19, 1928 and granted to The Gimson Shoe Machinery Company Limited and Walter Joseph Miller Underwood.

Journalized in bearings in the head 28 is a transverse shaft 112, carrying near its right-hand end the gear 110 which meshes with the gear 48, and carrying at its left-hand end, vertically above the toothed sections 50 of the feed wheel 20, the presser wheel 22 which is of brass and has a smooth periphery. As mentioned previously, the work is fed through the machine between the feed wheel 20 and the presser wheel

22. In order that the work may be gripped between the feed wheel 20 and the presser wheel 22 the head 28 is urged downwards by a coil spring 114. The spring 114 surrounds a rod 116 which passes upwardly through a projection 118 on the lug 36 of the frame 32 and is confined between a washer 120, which engages the underside of the projection 118, and a collar in the form of a nut 122 threaded on the lower end of the rod 116. The upper end of the rod 116 has integral therewith a square block 124 in which are formed two horizontal bores the axes of which pass relatively close one above the other and each axis being perpendicular to a line parallel to the other. A bolt 125 which may be passed through either bore (after suitably turning the rod 116) and then into a bore in the head 28 of the machine serves to complete the connection between the spring 114 and the head 28. The provision of two holes in the block 124 as described admits of rapid change in the value of the pressure of the spring 114 when desired, or, alternatively enables the machine to be set to accommodate thick work pieces while not requiring a correspondingly large movement of a lever 126 by which the head 28 may be lifted. The lever 126 is pivoted on a transverse stud extending from the stationary frame 32. The forward end of the lever 126 underlies the lower end of the rod 116, as shown in Fig. 1, while a treadle rod 65 couples the rear end of the lever 126 to a second treadle 67 pivoted on the floor plate 55 aforesaid. Depression of the treadle 67 serves to swing the left-hand end of the head 28 upwardly about the pin 106 to allow the introduction of work between the presser wheel 22 and the feed wheel 20. Downward movement of the head 28 is limited adjustably by a stop screw 128 threaded into the lug 36 of the frame 32.

Mounted for vertical sliding movement near the left-hand end of the head 28 is a knife slide 130 (Fig. 1). The slide 130 is shaped as an inverted U, comprising a horizontal bridge piece and two vertical limbs 132 (Figs. 1 and 6) and 134 (Figs. 2 and 6). The slide 130 is adjustable vertically relative to the head 28 by means of an adjusting screw 136 which is threaded into the head 28 and which has a large cap 138 by which it may be turned. The cap 138 may conveniently carry graduations upon its upper surface which register with an index mark on a stud 140 on the head 28 and indicate the extent of the vertical movement imparted to the slide 130. Relative vertical movement of the slide 130 and the screw 136 is prevented by a shoulder 142 on the screw which abuts the under side of the horizontal bridge piece of the slide 130 and by the engagement with the top of the said bridge piece of a collar 144 which forms part of the cap 138. The vertical links 132 and 134 extend downwardly in front of and rearwardly of, respectively, the right-hand end portion of the head 28 which they embrace. The limb 132 carries the channeling knife 26 while the limb 134 carries the grooving knife 30. A pair of compression springs 145 seated in recesses in the head 28 bear upwardly against the under surface in the above-mentioned bridge piece and take up any play in the threads of the screw 136 and prevent undesired turning of the screw. The slide 130 may be secured in adjusted position by turning a knurled nut 146 (see Fig. 6), which is threaded on a stud 148. The stud 148 passes through a bore in the head 28 and through slots in the limbs 132 and 134 and has a collar 150 at its

rear end. Tightening of the nut 146 on the stud 148 draws the limbs 132 and 134 together to clamp them against the head 28.

The limb 134 of the slide 130, which carries the grooving knife 30, has a vertical guideway therein in which a slide 152 is mounted for vertical sliding movement, as shown in Fig. 2. The slide 152 carries the grooving knife 30 at its lower end and comprises an upper section 154 and a lower section 156 held together in fixed relation by a screw 158. The upper part of the section 156 overlaps the lower part of the section 154 and the screw 158 passes through a key-hole slot 160 in the section 156 and is threaded into the section 154. When the screw 158 is tightened the sections 154 and 156 of the slide 152 are effectively integral, but when the screw 158 is released the section 156 may be lowered relatively to the section 154, the upper enlarged part of the slot 160 passed over the head of the screw 158 and the section 156 detached from the machine together with the grooving knife 30 which is attached thereto. This arrangement allows the grooving knife to be repositioned without difficulty after it has been removed, with the section 156, for sharpening.

The slide 152 is retained in its guideway in the limb 134 by plates 162 which overlap the section 154 and are secured to the limb 134 by screws 164. The heightwise position of the slide 152 in its guideway is controlled by a pair of lower and upper toggle links 168 and 170 respectively. The lower link 168 is connected at its lower end by a pivot 166 to the upper end of the slide 152 and at its upper end to the link 170 by a pivot 174. Extending approximately horizontally from the upper link 170 at a locality adjacent to the pivotal connection 174 is an arm 172, the link 170 together with the arm 172 constituting a bell crank fulcrumed on the pivot 174. The upper end of the link 170 is connected by a pivot 176 to the lower part of a bolt 178 which, in turn, is adjustably secured to a lug 180 integral with the limb 134 by nuts 182 and 184 threaded on the bolt 178 and engaging the upper and lower sides of the lug.

It will be apparent that the above-described arrangement enables the toggle 168, 170 when broken to hold the grooving knife 30 in an elevated (and inoperative) position, and when straightened to maintain the knife 30 in a lowered and operative position. Actuation of the toggle 168, 170 is effected by a third treadle 185, depression of which pulls down a treadle rod 186 which is coupled at 188 to a long arm 190 of a bell crank lever 190, 192 connected to the head 28 by a pivot 194. A short arm 192 of the bell crank lever 190, 192 is connected by a pivot 196 to one end of a connecting rod 198 the other end of which is connected by a pivot 200 to the arm 172 of the bell crank lever 170, 172. The arrangement is such that depression of the treadle 185 swings the bell crank lever 190, 192 in a counterclockwise direction (as seen in Fig. 2) about its pivot at 194 thereby causing the rod 198 to break the toggle 168, 170 and the knife 30 to be moved into an inoperative position. Such counterclockwise movement of the bell crank lever 190, 192 is limited by contact of an adjustable stop screw 202 threaded into the head 28 with the arm 192. When the treadle 185 is released the bell crank lever 190, 192 moves in a clockwise direction (as seen in Fig. 2) about its pivot at 194, under the action of a tension spring 204 interposed between the arm 192 and the head

28, until the toggle 168, 170 has been straightened into the position shown in Fig. 2. Further movement toward the left (as seen in Fig. 2) is prevented by contact of a surface on the link 168 with a surface 206 on the section 154 of the slide 152 and the toggle 168, 170 then serves to hold the knife 30 and the limb 134 in fixed relation.

Should provision for moving the grooving knife 30 out of operative position not be required, the link 168 and the bell crank lever 170, 172 may be removed and the pivots at 176 and 166 joined by a single link, the treadle 185 and associated parts being dispensed with.

At its lower end the lower section 156 of the slide 152 has an extension 208 in the form of a split clamp suitably shaped to allow forward and rearward sliding therein of a square block 210 (prior to clamping in position). The forward face of the block 210 is formed as a small disk 212 (Fig. 4), and sliding axially through a bore in the block is a sleeve having a disk 214 integral therewith at its forward end. The sleeve has an internal screw thread which accommodates a clamping screw 216 part of the head of which is received in a recess countersunk in the rear end of the block 210. By tightening the screw 216 the disks 212, 214 may be urged together. The grooving knife 30 which is formed in the usual manner of a sharp-ended tube is integral with a U-shaped blank 218 (Figs. 2 and 4), which is gripped between the disks 212 and 214, the U-shaped blank 218 fitting loosely round the sleeve last mentioned and allowing a certain measure of arbitrary adjustment of the knife 30 relatively to the slide 152, prior to clamping by the screw 216.

The front limb 132 of the knife slide 130 has formed therein an arcuate groove 220 in which slides a correspondingly shaped tongue which forms part of a knife-supporting sector 222. The sector 222 is held in adjusted position on the front of the limb 132 by screws 223 threaded into the limb 132, the sector having an arcuate slot to accommodate the shanks of the screws and the screws having enlarged heads which engage the forward side of the sector. The sector 222 has a rearwardly extending part 226 (Fig. 4), in which are formed two parallel forwardly and rearwardly extending bores. At the rear end of this rearwardly extending part 226 is a clamping plate 224 from which two parallel sleeves 227 (one of which is indicated in Fig. 4) extend into the bores in the part 226. The sleeves 227 are internally screw-threaded and the clamping plate 224 is urged towards the rear end of the part 226 of the sector 222 by screws 228 passing into the bores, engaging the internal screw threads in the sleeves 227 and having enlarged heads abutting the forward side of the sector 222. The channeling knife 26, which may be of the usual form comprising a W-shaped blank with a cutting blade at one of the lower corners, is clamped between the clamping plate 224 and the rear end of the rearwardly extending part 226 of the sector 222 by the screws 228. The arms of the W-shaped blank are separated by distances greater than the diameters of the sleeves 227 which they embrace, thereby providing for a certain amount of arbitrary adjustment in a vertical plane (which may include adjustment transversely, vertically or angularly, severally or in combination) between the knife 26 and the sector 222. However, with the adjustments provided on the machine the arbitrary setting of the knife just referred to

become unnecessary, controlled adjustment being provided to suit all requirements. Consequently a knife blank having merely a pair of spaced holes which fit closely on the sleeves 221 may be used, and as a result the skill customarily necessary in performing the arbitrary setting of the knife 26 relatively to the sector 222 is not required since, as will be appreciated, the knife can be placed in any desired position of adjustment transversely, vertically or angularly by independent adjustments as will be more particularly pointed out. Shims, such as 230 (Fig. 4), may be inserted at either or at both sides of the knife blank to position the knife 26 in the desired forward and rearward relation with regard to the presser foot 24.

The arcuate groove 220 and the arcuate slot through which the screws 223 pass have their center approximately at the tip of the blade of the channeling knife 26. In this way the angle at which the channel is cut is readily adjustable by sliding the tongue of the sector 222 round the arcuate groove 220, this adjustment not affecting substantially the other settings of the knife. By removing the two screws 223 which are threaded into the limb 132 and hold the sector 222 in place thereon, the sector 222 may be released from the slide 130 for the purpose of sharpening the knife 26, which is removed as a unit with the sector 222. In order that the sector 222 may be returned, after the sharpening, to its previous position on the slide 130, the limb 132 has adjustably secured thereto an arc-shaped piece 232 having therein a slot of the same curvature as that of the arcuate groove 220. A screw passing through this slot secures the arc-shaped piece in adjusted position upon the limb 132. The piece 232 is adjusted when the sector 222 is adjusted and its securing screw then locked; the piece 232 has a stepped part which normally cooperates with a stepped part of the sector 222, as indicated by the numeral 234 on Fig. 1. When the sector 222 has been removed and is to be replaced, care is taken that the stepped parts of the piece 232 and sector 222 cooperate in the manner shown in Fig. 1, thereby insuring that the sector 222 is in its previous position of adjustment. Consequently the channeling knife 26 need not be set afresh.

The presser foot 24 of the machine is secured close to the forward end of the head 28. It comprises a straight bar and a rearwardly extending curved end part of substantially the same curvature as the periphery of the presser wheel 22. Vertical adjustment of the presser foot 24 relatively to the head and to the presser wheel 22 is provided for by clamping screws 236 passing through vertical slots in the presser foot and threaded into the head. Engaging the top of the presser foot 24 is a screw 238 threaded into the head 28, whereby the adjustment is maintained and facilitated. It is usually desired that the under surfaces of the presser foot 24 and of the presser wheel 22 should be at the same level. This adjustment may be effected by the parts above described. It is further usually desired that the presser foot 24 should press upon the work right up to the edge of the work and so the right-hand side of the presser foot 24 will commonly be adjacent to the operative part of the edge gage 76. If the head 28 has been adjusted transversely to the right, then the substitution of a narrower presser foot will be desirable to prevent the presser foot fouling the edge gage and adjustment of the head 28 to the left will allow the use of a wider presser foot.

It will be seen that in the illustrated machine various adjustments are provided for each of the two knives 26 and 30 and that these adjustments may each be effected without affecting other adjustments. Considering first the channeling knife 26, this may be conveniently adjusted vertically with regard to the presser foot 24 by rotation of the screw 136 with the large graduated cap 138, thus varying the depth of the channel below the upper side of the work (in the case of outsoles this side will normally be the grain side). Alteration in the distance of the channel from the edge is provided, for example, by the transverse adjustment of the head 28 of the machine relative to the main frame 32 and is controlled by the screw 98 threaded transversely in the lug 96 of the head 28. This transverse adjustment of the head 28 also allows compensation to be effected when the knife 26 has been sharpened. The adjustment of the angle of the channeling knife 26 is facilitated by the mounting of the knife 26 on the sector 222 which engages the arcuate groove 220 in the slide 130.

With regard to the adjustments of the grooving knife 30, which cuts a stitch-receiving groove 25 at the base of the channel, the above-described arbitrary adjustment may be used to ensure that the cutting portion of the knife will lie behind the tip of the channeling knife. Heightwise adjustment of the grooving knife 30 relatively to the channeling knife 26 is effected by adjusting the nuts 182 and 184 which determine the heightwise position of the slide 152 in its guideway. The above-mentioned transverse adjustment of the head 28 of the machine does not destroy the relationship between the two knives 26 and 30 but moves them transversely as a unit. Similarly, adjustment of the screw 136 does not destroy the relationship between the knives 26 and 30 but moves them vertically as a unit.

It may also be desired, in operating upon outsoles, that the channel cut by the channeling knife 26 should be further from the edge of the sole in the shank portion than in the forepart. To perform a channeling operation of this nature upon the outsole the operator first depresses the treadles 61 and 51 to elevate the head 28 and to hold the edge gage 76 to the right. He then introduces the sole between the presser wheel 22 and the feed wheel 20 at a point near the heel breast line, with the toe end of the sole towards him. Keeping the sole well pressed against the edge gage 76 with his left hand, he releases the treadle 67 to lower the head 28 and turns the driving shaft 38 so that the sole is fed away from him. When a point near the ball line is reached the treadle 51 is released, causing the edge gage 76 to move to the left and to move the sole to the left along with it, thereby bringing the channel which is being cut closer to the edge of the sole. It will be noted that in the illustrated machine the feed wheel 20 and the edge gage 76 move together as a unit on depression or release of the treadle 51, thereby avoiding any damage to the sole which might result from relative movement between the sole and the teeth of the feed wheel. The channel is continued around the forepart of the sole and, on reaching the ball line on the other side of the sole, the treadle 51 is again depressed, and the edge gage 76 returned to the right together with the feed wheel assembly. On approaching the heel breast line again, the rotation of the driving shaft is discontinued and the sole removed from the machine after depression of the treadle 67.

Having thus described my invention, what I claim as new and desire to secure by Letters Patent of the United States is:

- 5 1. A sole fitting machine comprising a tool for operating upon a sole, a feed wheel for supporting the sole and feeding the sole past said tool, a driven shaft upon which said feed wheel is slidably keyed, a rotary edge gage for positioning the sole relatively to said tool, a driving connection between the feed wheel and the edge gage for rotating the edge gage in a direction to assist in feeding the work, a guide in which said edge gage is mounted for movement in a direction parallel to said shaft, a connection between said edge gage and said feed wheel for causing the edge gage and the feed wheel to be moved together in a direction parallel to the feed wheel shaft, a spring acting upon said edge gage to urge said edge gage and said feed wheel as a unit in a direction parallel to the feed wheel shaft to a stop position, and means for moving said edge gage and said feed wheel as a unit away from said stop position, said means including an operator-controlled lever connected with the edge gage for moving the edge gage and feed wheel away from said stop position against the force of said spring.
- 10 2. A sole fitting machine comprising a tool for operating upon a sole, a feed wheel for supporting the sole and feeding the sole past said tool, said feed wheel having a hub with a circumferential slot therein, a driven shaft upon which said feed wheel is slidably keyed, a rotary edge gage, a supporting block in which said edge gage roll is rotatably mounted, a driving connection between said feed wheel and said edge gage for rotating said edge gage in a direction to assist in feeding the work, a guide in which said edge gage is slidably mounted for movement lengthwise of the feed wheel shaft, a yoke extending from said edge gage supporting block and engaging the slot in said hub to cause the feed wheel to move along its driving shaft when the edge gage supporting block is moved lengthwise of said driving shaft, a spring acting upon said edge gage supporting block to cause the edge gage roll and the feed wheel to move as a unit lengthwise of said driving shaft, an operator-controlled lever connected to said edge gage supporting block for retracting said edge gage roll and said feed wheel against the force of said spring, and a pair of adjustable stops engageable with said lever to limit the extent to which the edge gage and the feed wheel can be moved by the spring and retracted by the lever.
- 15 3. A channeling machine comprising a sole support, a head, a slide mounted in said head for heightwise adjustment toward and from said sole support, a channeling knife carried by said slide, a grooving knife, a slide upon which said grooving knife is carried, said channeling knife slide having a guideway in which said grooving knife slide is mounted for relative heightwise movement, a toggle mechanism for moving said grooving knife slide relatively to said channeling knife slide, and operator-controlled means for breaking and straightening said toggle to move the grooving knife slide relatively to the channeling knife slide.
- 20 4. A channeling machine comprising a sole support, a head mounted for heightwise movement toward and from said sole support, means for controlling the heightwise position of said head relatively to said sole support in accordance with local variations in the thickness of a

sole being operated upon, a slide mounted in said head for relative heightwise adjustment toward and from said sole support, a channeling knife carried by said slide, a grooving knife, a slide upon which said grooving knife is carried, said channeling knife slide having a guideway in which said grooving knife slide is mounted for relative heightwise movement, a pair of toggle links pivotally connected to each other, one of said links being pivotally connected to said channeling knife slide and the other of said links being pivotally connected to said grooving knife slide, said toggle links being arranged to cause relative heightwise movement of said channeling knife slide upon transverse movement of the pivotal connection between said links, resilient means including a stop for maintaining said toggle links in substantially straightened relation with the grooving knife down in operating position, and operator-controlled means for breaking the toggle formed by said links to raise said grooving knife.

5 5. In a channeling machine, a carrier for a channeling knife, a support in which said knife carrier is slidably mounted for arcuate movement to enable the inclination of the knife to be adjusted, means for securing said carrier to said support in adjusted position, a stop engageable with said carrier to limit arcuate movement of the carrier in one direction, and means for adjustably securing said stop to said support to stop said carrier at any desired position of adjustment of the inclination of said knife, thereby enabling the operator to replace the knife carrier after removing the same from said support in the same position of adjustment which the knife carrier occupied before removal.

10 6. In a channeling machine, a slide constructed and arranged to carry a grooving knife, a support having a guideway in which said slide is mounted for relative heightwise movement, a pair of links pivotally connected to each other to form a toggle, the lower end of one of said links being pivotally connected to said slide and the upper end of the other link being pivotally connected to said support, and operator-controlled means for breaking and straightening said toggle to vary the heightwise position of the grooving knife.

15 7. A sole fitting machine comprising a stationary frame, a sole support carried by said frame, a head adapted to carry a tool for performing a sole fitting operation, said head being mounted on said stationary frame with provision for heightwise movement of the head in accordance with local variations of thickness of soles fed through the machine, a rod pivotally connected to said head, said rod extending downwardly from said head through an opening formed in said frame, a collar adjacent to the lower end of said rod, a compression spring surrounding said rod and interposed between said collar and said frame, an adjustable pin connection between said rod and said head whereby the operating tension on said head may be readily adjusted, a stop for limiting downward movement of said head under the influence of said spring, a lever arranged for abutting engagement with the lower portion of said rod, and a treadle mechanism for operating said lever to urge the rod upwardly and thereby to raise the head against the force of said spring.

20 8. In a sole fitting machine having a stationary frame carrying a work support and a tool-carrying head movable heightwise in accordance with variations in the thickness of the work, a tensioning member for holding down said head com-

prising a rod adapted to be pivotally connected to the head and to pass through an opening in the frame, a collar on the lower end of the rod, and a compression spring surrounding said rod and adapted to be interposed between the frame and said collar to tension the rod, the rod having two holes in its upper end portion for alternatively receiving a pivotal connection to the head, which holes are located at slightly unequal distances

from said collar and the axis of either hole being substantially perpendicular to a line drawn parallel to the axis of the other hole, said holes, enabling the operator by changing the pivotal connection from one hole to the other by a quarter turn of the rod to effect a quick adjustment of the operating tension of the member.
